UNITED STATES PATENT OFFICE

2,002,926

ELECTRODYNAMIC LOUD SPEAKER

Lincoln Thompson, Naugatuck, Conn.

Application July 30, 1932, Serial No. 626,416

12 Claims. (Cl. 179—115.5)

This invention relates to devices for translating electrical oscillations into mechanical vibrations, or the reverse for use in radio loud speakers, telephone receivers and transmitters, 5 microphones and the like, consisting of an "electrodynamic" device in which a movable conductor, free to vibrate in an intense magnetic field, is caused to carry electrical currents of audio frequency.

10 One object of this invention is to provide an electrodynamic acoustic vibrator of the above nature, in which the inductance and total impedance of the audio frequency circuit and the mechanical inertia of the moving element will be 15 of very small magnitudes, whereby the transmission of oscillations will be carried out with a high degree of fidelity and efficiency.

A further object is to provide a device of the above nature in which inactive material is excluded from the air gap, whereby a most efficient 20 use will be made of the conducting material of the audio frequency circuit.

25 A further object is to provide a device of the above nature in which the vibrating conductor and associated leads are adapted to be stamped out of a single blank, giving a uniform and inexpensive product.

30 A further object is to provide a device of the above nature which will be simple and rugged in construction, inexpensive to fabricate and assemble, light in weight, ornamental in appearance, and very dependable and durable in service.

In the drawing:

35 Fig. 1 represents a sectional view of an electrodynamic acoustic vibrator embodying the invention.

Fig. 2 is a perspective front view of the transformer and vibrating element, as it appears with the loud speaker cone detached therefrom.

40 Fig. 3 is a sectional rear view of the vibrating unit with the transformer and core plate omitted.

Fig. 4 is a sectional view of a modified form of the connector between the single coil transformer secondary and the lead strips for conducting the 45 current to the movable single coil vibrating ring.

Fig. 5 is a sectional view of a modification.

Previous commercially successful electromechanical devices of the above nature have been of three general types, the electromagnetic, the 50 electrodynamic and the electrostatic. In each of the first two types it is essential that there exist a linkage of an electrical circuit with magnetic flux, thus introducing into the circuit the property of inductance, while the electrostatic type is 55 essentially a condenser (one of whose plates is

vibratory), having the property of capacitance. It is a well known fact that the total impedance of any circuit having reactance, either in the form of inductance or capacitance, will vary with the value of the applied frequency, and that therefore the response of such a circuit to a voltage of varying frequency will not faithfully represent the variations in value of the voltage. 5

It is further well known that certain types of vacuum-tube amplifiers used in conjunction with 10 radio loud speakers function efficiently over only a small range of impedance load values in their output circuits, so that it is difficult to obtain uniform performance of the amplifier over the wide band of frequencies desirable for the faithful 15 reproduction of speech or music.

From the above it will be seen that it is doubly important for the impedance of the audio frequency circuit of such devices to maintain a substantially constant value throughout the whole 20 range of frequencies to which it must respond. Since the total impedance value of an electrical circuit represents a combination of resistance and reactance values, and since the resistance component does not vary with frequency, it follows that by having a relatively low value of ratio 25 of reactance to resistance, the variation of impedance with frequency will be minimized. For this reason the practice of deliberately introducing resistance into the circuit is sometimes resorted to, but only at a material sacrifice of efficiency in the translation. 30

By means of this invention the total amount of inductive reactance inherent to the electrodynamic movement has been greatly reduced, 35 with the resulting production of a device whose impedance variation with frequency is much lower than with previous devices of this character.

In loud speakers in general, where use is made 40 of a wound coil of a large number of turns, it is, of course, essential that a certain portion of the space within the air gap be occupied by inactive material in the form of insulation, whereas in the type embodied in this invention, the 45 vibrating element, consisting in a single closed ring of metal, requires no insulation within the air gap, allowing the space to be used with a maximum of efficiency, and incidentally permits of a very rugged and inexpensive type of construction. 50

Referring now to the drawing, in which like 55 reference numerals denote corresponding parts throughout the several views, the numeral 11 (Figs. 1 and 3) indicates an iron yoke having pole

pieces 12 and 13, with cylindrically curved opposing faces. Symmetrically positioned therebetween is a cylindrical iron core 14, leaving a pair of annular substantially semicircular air gaps 15 and 16 between the respective pole pieces and the iron core. The core 14 is firmly fixed in position relative to the yoke by a plate 17 of non-magnetic material, secured to the rear surface of the core by screws 18 and to the rear surface of the pole pieces 12 and 13 by screws (not shown) threadedly engaged with tapped holes 19 in said pole pieces. The yoke 11, with its pole pieces 12 and 13, the core 14, and the air gaps 15 and 16, together constitute a magnetic circuit, adapted to be excited by two magnetizing coils 20 and 21, energized by a battery 21a or other direct current source. The coils 20 and 21 are interconnected in such a manner that their polarities are additive about the magnetic circuit, producing a field similar in its distribution throughout the iron parts and the air gap to that of the well known bipolar dynamo-electric machine.

Symmetrically disposed in the annular space provided by the two air gaps 15 and 16 is a vibrating element 22 formed in the shape of a continuous ring of highly conductive non-magnetic material, such as copper, aluminum, silver or the like, said ring 22 having integrally formed thereon a plurality of upturned lugs 23, adapted to be attached to a cone diaphragm or other sound-radiating member. Supporting the vibrating ring 22, and integrally attached thereto are a pair of bifurcated curved flexible conducting strips 25 and 26, adapted to conduct electrical currents to and from the vibrating ring 22 at diametrically opposite points.

The dimensions and curvature of the strips 25 and 26 are such as to allow the ring 22 to vibrate freely in an axial direction within its range of vibration. The ring 22 and flexible strips 25 and 26 are preferably formed from a single piece of material, making for simplicity of production and uniformity of quality.

For the purpose of furnishing a rigid support for the flexible conducting strips 25 and 26, and thus maintaining the vibrating ring 22 concentrically within the air gaps 15 and 16, the ends of said strips are secured to bent-over transverse portions 27 and 28 of a pair of T-shaped angular conducting plates 27a and 28a, as indicated in Figs. 1 and 2. The plates 27a and 28a have parallel "stem" portions separated by a thin sheet of insulating material 29, such as rubber, and said stem portions are adapted to pass through a central rectangular opening formed in an insulating block 30 to which said stems are secured by screws 31. The block 30, in turn, is adapted to pass through a centrally located rectangular recess in the core 14, and has an integral flange portion 32, adapted to fit into a recess in the forward face of said core, and to be secured therein by screws 33.

The outwardly-extending bent-over transverse portions 27 and 28 of the T-shaped plates 27a and 28a lie in a plane parallel to that of the front surface of the core 14, and are drilled and tapped at their outer ends, forming abutments adapted to receive the extended portions of the bifurcated members 25 and 26, which are secured thereto by screws 34 passing through washers 35, the latter tending to relieve twisting strains upon the metal of members 25 and 26 when being assembled, and also to improve the electrical contact between the abutments and the conducting members.

It will be seen that there is thus provided a rigid

mechanical structure adapted to furnish a secure support for the strips 25 and 26 connected to the vibrating ring 22, thus maintaining said ring concentrically within the air gaps 15 and 16, but permitting it to vibrate axially within the range of its travel.

As a means of transmitting the mechanical vibrations of the ring 22 to the ambient air in the form of sound waves, provision is made of a conical diaphragm 36 of the conventional type, formed of parchment or the like, and cemented or otherwise secured at its inner end to the lugs 23 of the vibrating element 22. The outer end of the diaphragm 36 is resiliently supported by a ring 37 of thin leather or similar material, held between a pair of circular clamping plates 38 and 39 by means of bolts 40. The inner plate 39 is rigidly attached to the main field structure by a plurality of brackets, one of which is indicated in Fig. 2 by the numeral 41.

For the purpose of completing the electrical circuit through the ring 22 and causing electrical currents to flow therein, there is provided a transformer 42, having a primary coil 43 of a relatively great number of turns, and a secondary coil 44 having a single turn in the form of a massive cylindrical conducting loop, said coils being separated by an insulating layer 45, such as rubber, and being surrounded by a magnetic core 46 embracing both coils 43 and 44. The terminals of the secondary coil 44 are adapted to be secured to the rear ends of the plates 27a and 28a as by screws 47 threadedly engaged with the same but terminating short of the insulating sheet 29. Under some conditions, the joint between the secondary coil 44 and the conducting plates 27a and 28a may be eliminated, and the parallel conducting plates 27a and 28a may be formed integral with the secondary coil 44 as shown in Fig. 4, thus simplifying the construction and somewhat reducing the electrical resistance of the circuit.

Operation

When the field coils 20 and 21 are energized with direct current from the battery 21a the field structure will become magnetized in a manner similar to that of a bipolar dynamo, the magnetic flux entering the core 14 from one of the two pole pieces 12 and 13, emerging from the core toward the other pole piece, and completing its circuit through the yoke 11.

It will be understood that the amplified alternating or oscillatory currents derived either from a microphone, a phonograph "pickup", or a radio system etc. will pass through the primary winding 43 of the transformer 42 and induce in the secondary winding 44 electromotive forces adapted to produce in the electrical circuit formed by the plates 27a and 28a, the flexible members 25 and 26, and the vibrating element 22, currents of similar wave-form but of much greater magnitude than the original currents.

The relative directions of current flow in the electrical circuit at a certain selected instant are shown by the arrows in Fig. 2, where it will be seen that an element of current considered as emerging from the upper side of the transformer secondary winding 44 enters the T-shaped plate 27a, flows toward its forward end, divides along the transverse portion 27 and flows upward through the curved strips of the bifurcated flexible member 25 to their junction point where connection is made with the annular vibrating ring 22. At this point the two portions of cur-

rent unite and again divide, flowing in substantially equal parts down the two sides of the ring to the opposite junction point with the flexible bifurcated strips 26, and thence upwardly through said strips, returning by way of the lower plate 28a to the secondary winding 44 of the transformer 42 and thus completing the circuit.

It will be observed that the flat parallel conducting plates 27a and 28a are disposed in such a manner that no inductive "loop" is formed between them. Again, it will be noted that since the flexible conducting strips 25 and 26 are well spaced apart and kept as close as possible to the return paths of the currents through the vibrating ring 22, a similar result is produced. By means of this construction, it will be seen that the inductive effect of the interconnecting portions of the circuit will be maintained at a minimum value. It will be observed, moreover, that the current in the vibrating ring 22, instead of flowing completely around the core 14, (an arrangement which would produce a "loop" circuit around a mass of iron, and thus make for high inductance) divides into two parts flowing in opposite directions about the circumference of the core, an arrangement which reduces the inductive effect to the minimum.

By means of this construction it will be seen that not only will the resistance of the circuit be kept low, by the provision of ample cross-section and short paths for the current, but in addition by the avoidance of "loops" either with or without included magnetic material, the inductance of the circuit will be maintained at a minimum value. It therefore follows that the tendency of the impedance of the circuit to vary with impressed frequency is minimized, and currents flowing in the vibrating element 22 will tend faithfully to represent the voltage applied to the amplifier.

From the well-known principle of the electric motor it will be seen, that the tendency of current flowing in the vibrating ring 22, as it lies in the strong magnetic field in the air gaps, will be to simultaneously impart to each side of the ring a thrust, perpendicular to the directions of both the field flux and the current, or axially of the ring. Moreover, it will be observed that the direction of thrust on each side of the ring in the air gaps 15 and 16 will be the same along its axis, so that when receiving current of one polarity from the transformer, the vibrating element will be urged forward, while when the current of the opposite polarity is received it will be urged backward. The mechanical vibrations of the ring 22 will thus be caused to faithfully follow the oscillations of the current flowing in the windings of the transformer 42, the flexible members 25 and 26 bending sufficiently to permit the vibratory motion without allowing any other displacement of the vibrating element.

It will be understood that the conical diaphragm 36, rigidly fixed to the vibrating element, will partake of its vibratory motion, and impart this motion in greater volume to the surrounding air, thus completing the translation of the electrical impulses applied to the vibrating ring into audible sound waves.

In Fig. 5 a modified form of the invention is disclosed wherein an electrodynamic ring 48, surrounding a core 48a, is connected to a source of oscillating current by a pair of outwardly extending flexible conductor strips 49 and 50, said strips being preferably made integral with said ring 48. The radial strips 49 and 50 are joined

to the secondary coil 51 of a transformer unit 52 by short and long conducting plates 53 and 54 respectively. The long conducting plate 54 is adapted to lie parallel and in close proximity to the radial strips 49 and 50 to reduce inductive forces therebetween. As clearly shown in Fig. 5 the extremities of the strips 49 and 50 are oppositely offset at 55 and 56 and are attached to the ends of the conductor plates 53 and 54, as by screws 57 and 58.

While there have been disclosed in this specification two forms in which the invention may be embodied, it is to be understood that these forms are shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In an electrodynamic acoustic vibrator, a magnetic field structure having air gaps, a closed circular conducting ring positioned in said air gaps, a source of oscillatory currents, and substantially non-inductive means comprising a pair of parallel flat strips adapted to carry said currents from said source to said ring.

2. In an electrodynamic acoustic vibrator, a magnetic field structure having air gaps, a source of oscillatory currents, a closed circular conducting ring positioned in said air gaps and adapted to provide a plurality of paths electrically in parallel for said currents, and substantially non-inductive means comprising a pair of parallel flat strips adapted to conduct said currents between said source and said ring.

3. In an electrodynamic acoustic vibrator, a magnetic field structure including a centrally apertured cylindrical core, a plurality of stationary conductors in substantially non-inductive relationship passing through said aperture, an annular conductor completely surrounding said core but free to move axially in relation thereto, flexible conductors within said ring adapted to support said annular conductor and to form electrical connection between the same and said stationary conductors.

4. In an electrodynamic acoustic vibrator, a bipolar field structure having a cylindrical core and air gaps, a circular closed conducting ring adapted for axial vibration within the air gaps of said field structure, flexible conducting means attached at diametrically opposed points to said ring, a transformer, and a pair of flat conductors located with their faces close together and adapted to furnish electrical connection between said transformer and said flexible conducting means.

5. In an electrodynamic acoustic vibrator, a field structure having two arcuate air gaps magnetically in series and geometrically opposed on a common circle, means for magnetizing said structure transversely of said circle, a circular closed conducting ring adapted to lie within said air gaps and to move axially therein, flexible conducting means within said ring formed integral with and attached at diametrically opposed points to said ring, a source of oscillating currents, and substantially non-inductive means adapted to connect electrically said current source and said flexible conducting means, said air gaps extending substantially around the entire circumference of said ring.

6. In an electrodynamic acoustic vibrator, a field structure having a plurality of arcuate air gaps disposed about a common circle, means for magnetizing said structure, a closed circular conducting ring adapted for axial vibration within the air gaps of said structure, flexible conducting means within and attached to said ring, a source of oscillating currents, and substantially non-inductive means adapted to connect electrically 5 said current source and said flexible conducting means comprising a pair of parallel flat strips, and an acoustic diaphragm mounted upon and adapted to vibrate with said ring.
7. In an electrodynamic acoustic vibrator, a transformer having a primary winding, a magnetic circuit, and a secondary winding, and adapted to function on currents having frequencies within the audible range, a magnetic field, a conductor in the form of a closed circular ring 10 mounted for free axial vibration within said magnetic field, and a pair of flat conducting leads located with their faces close together for providing electrical connection between said transformer and diametrically opposed points on said ring.
8. In an electrodynamic acoustic vibrator, a circular closed ring of conducting material having a plurality of inwardly extending flexible conductors circumferentially disposed therearound 15 and adapted to provide a plurality of arcuate current paths electrically in parallel in said ring, means for providing a magnetic field adapted to traverse said ring, and means for causing a flow of oscillatory currents in said flexible conductors and in said ring, said air gaps extending substantially around the entire circumference of 20 said ring.
9. In an electrodynamic acoustic vibrator, a field structure having a plurality of arcuate air gaps disposed about a common circle, means for magnetizing said structure, a closed conducting 25

ring adapted for axial vibration within the air gaps of said structure, flexible conducting means within and attached to said ring, a source of oscillating currents, a pair of flat insulated strips adapted to connect electrically said current source and said flexible conducting means, and an acoustic diaphragm mounted upon and adapted to vibrate with said ring. 5

10. In a loudspeaker, a magnetic field energized by a constant source of direct current, an electrodynamic ring located in said field and adapted to vibrate freely in a direction at right angles to said field, a diaphragm connected to said ring, a plurality of flexible current conducting strips each of which is connected at its outer end to 10 said ring, means for rigidly supporting the inner ends of said strips, and means for passing an oscillating current through said strips and ring to cause said diaphragm to vibrate, said flexible strips lying in a circle concentric with said ring 15 to minimize induction.

11. In an electrodynamic acoustic vibrator, a circular closed metal ring having a plurality of arcuate electrically parallel current paths, a plurality of flexible conductors connected to said 20 ring at regularly spaced points, a plurality of magnetic air gaps surrounding said ring, and a pair of stationary conductors arranged parallel to each other for causing a flow of oscillatory currents in said conductors and in said ring. 25

12. In an electrodynamic acoustic vibrator, a magnetic field structure including a core, a plurality of stationary conductors passing through said core, an annular conductor completely surrounding said core but free to move axially in 30 relation thereto, inwardly extending flexible conductors adapted to support said annular conductor and to form electrical connection between the same and said stationary conductors. 35
